UNITED STATES PATENT OFFICE

148,899

DESIGN FOR A PORTABLE ATOMIZER

Henry Charles Yaeger, Ridgewood, N. J., assignor
to Grand Products, Inc., New York, N. Y., a
corporation of New York

Application May 29, 1946, Serial No. 130,206

Term of patent 3½ years

(Cl. D83—1)

To all whom it may concern:

Be it known that I, Henry C. Yaeger, a citizen of the United States, residing at Ridgewood, in the county of Bergen and State of New Jersey, have invented a new, original, and ornamental Design for a Portable Atomizer, of which the following is a specification, reference being had to the accompanying drawing, forming part thereof, in which—Fig. 1 is a left hand side view of the atomizer showing my new design; Fig. 2 is a front view; and Fig. 3 is a right hand side view thereof.

I claim:

The ornamental design for a portable atomizer, as shown.

HENRY CHARLES YAEGER.
